UNITED STATES PATENT OFFICE.

FRANKLIN BENNETT, OF CANAL FULTON, OHIO, ASSIGNOR OF TWO-THIRDS
TO BILLINGS BROTHERS, OF SAME PLACE, AND TO THE OHIO STONE-
WARE COMPANY, OF AKRON, OHIO.

CROCK-PRESS.

SPECIFICATION forming part of Letters Patent No. 399,178, dated March 5, 1889.

Application filed December 24, 1887. Serial No. 258,903. (No model.)

To all whom it may concern:

Be it known that I, FRANKLIN BENNETT, a citizen of the United States, residing at Canal Fulton, in the county of Stark and State of Ohio, have invented a new and useful Improvement in Crock-Presses, of which the following is a specification.

My invention has relation to improvements in that class of machines for making stone-ware crocks, in which the crock is formed by forcing the clay, in a plastic state, into a mold consisting of an inner core and an outer core, which form the rim and side walls, and cutting off the clay beyond the end of the core, leaving a bottom on the crock. Heretofore this mechanism has consisted of a press for forcing the clay and a single mold used in connection therewith.

The objects of my invention are to increase the capacity of the press by providing a number of molds to be simultaneously filled thereby, to improve and simplify the mechanism of the molds, and to provide devices for removing the completed crock without injury.

My invention consists in the devices illustrated in the accompanying drawings, as hereinafter described and claimed.

In the accompanying drawings, in which similar reference-letters indicate like parts, Figure 1 is the lower end of a clay-cylinder having a head with multiple openings for the attachment of crock-molds; Figs. 2 and 3, a side elevation and plan, respectively, of the crock-mold and connected parts adapted to be connected with one of the openings in the cylinder-head; Fig. 4, a central longitudinal vertical section of the outer shell of the crock-mold; Fig. 5, an end elevation of the crock-molds opened; Fig. 6, an end elevation of the carriage and operating mechanism from a section line, *x x*, of Fig. 3; and Figs. 7 and 8, a central vertical section and an end elevation (open) of a mold having a removable lining.

In the accompanying drawings, A is the lower part of an ordinary clay-cylinder similar to those which constitute a part of a sewer-pipe press, on the bottom of which is bolted a head, B, having a number of lateral exit-

ports, C, each provided with a flange for connecting the crock-molds. On each of the exit-ports C is bolted a short pipe, D, of the same internal diameter, upon the outer end of which is fitted a sleeve, E, provided with a handle, *e*, by which it is revolved, its outer end when drawn back being in the same plane as the end of the pipe D. The sleeve E is retained on the pipe D, and its rotary and longitudinal movement thereon directed and limited by pins *d*, which project from the former and rest in segmental spiral slots *e'* in the latter, so that by alternate partial rotations of the sleeve E it will be projected beyond and drawn back even with the pipe D.

Opposite each sleeve E, and mounted on a base, F, is an outer case, G, of the crock-mold, of the same internal diameter as and in the same axial line with said sleeve, so arranged that when the sleeve is forced outward the two shall unite and form a continuous tube.

The case G consists of three segmental sections, the lower and shorter being attached to the base F, and the others hinged thereto and arranged to be clamped together by a locking device, *g*, the whole constituting a mold for the outside of the crock and rim.

Upon the base F is a sliding carriage, H, directed by a guide, *h*, and in which is journaled a shaft, J, in the same axial line of the case G, and bearing on the end next said case a closed cylinder, I, provided at the end farthest from said case with a rim, *i*.

The cylinder I is of proper size to form the interior of or core for the crock, and with the rim *i*, when carried into and against the case G, respectively, constitute with it the pot-mold.

The carriage H is moved toward and from the case G by a handle, L, pinion K, and rack *k*, and on the shaft J is a long pulley, P, which enables it to be revolved by a belt. (Not shown.)

In operation the clay-cylinder A is charged with plastic clay, and the sleeve E of each set of molds is forced outward against the case G. Pressure is then applied in the cylinder A, which forces the clay into the case G, simultaneously with which each cylinder I, being rapidly revolved by its pulley P, is also

forced therein and retained until the intervening space is filled with the plastic clay, which is spread and molded by the cylinder I. The pressure in the cylinder A is then 5 arrested, the cylinder I drawn back, the sleeve E withdrawn from the case G, and the body of clay cut off along the adjacent end of the case G, leaving a bottom on the completed crock therein. The case G is then unlocked 10 and opened, and the crock removed by any suitable means, after which the operation is repeated. To facilitate the removal of the crock and avoid injury to it in its "green" state I, employ a modified form of case G, as 15 shown in Figs. 7 and 8, in which the lower portion of the case consists of a semicircular shell, g', which fits in recesses in the other parts of the case, and with them constitutes the inner face thereof. In each side of the 20 shell g' are notches g'', which enable it to be grasped by hand.

In operation, when the case G is opened, as hereinbefore described, the crock remains on the shell g' and is removed with it.

25 I claim—

1. In a crock-press of the class designated, the combination, with a pipe projecting from the exit-port of a clay-forcing cylinder and a crock-mold consisting of an outer case and 30 an inner core opposite and in the axial line with said pipe, of a sleeve which envelopes the end of said pipe, provided with devices,

such substantially as shown, by which it is carried against and withdrawn from said outer case, substantially as and for the purpose 35 hereinbefore set forth.

2. In a crock-press of the kind described, the combination, with a clay-forcing cylinder, and an outer mold composed of segmental sections hinged and arranged to be locked together and connected at one end with an exit or discharge port of said cylinder, of a movable closed forming-cylinder mounted adjacent to and in alignment with the axis of the mold and a carriage for supporting said cylinder and for effecting the required movements thereof toward and away from the said mold, substantially as and for the purpose 40 specified.

3. The combination, in a crock-mold having an outer case, an inner core, and rim closing the space between them at one end, and in which the outer case consists of segmental sections hinged and arranged to be locked together, of a segmental removable 45 lining which fits in recesses in said case, substantially as shown, and for the purpose specified.

In testimony that I claim the foregoing I have hereunto set my hand.

FRANKLIN BENNETT.
